COIN AND TOKEN SEPARATOR

William Patzer, Chicago, Ill.

Application November 6, 1937, Serial No. 173,209

7 Claims. (Cl. 194—97)

This invention pertains to coin handling devices, and more particularly to a coin chute having a plurality of discharge or exit openings into which various coins or tokens are directed by selecting mechanism.

One of the important objects of the invention is the provision of fraud-preventive means for the aforesaid type of coin chute and which is operable by a coin moving toward a particular discharge opening to block another such opening.

Another object is the provision, in a coin chute of the type having a descending coin passage with a discharge opening for genuine coins and an adjacent opening for spurious coins, of a selector member positioned at the lower end of the chute near these openings and arranged to be engaged by coins passing out the spurious discharge opening to block the passage into the opening for good coins.

Still another object is the provision of fraud-preventive means in coin chutes of the type having a discharge opening for spurious and another adjacent opening for good coins and constructed to be engaged by a coin element moving toward or through the rejection opening, that is, the opening through which spurious or bad coins are discharged, to block the passage to the opening for good coins so long as the rejected or bad coin remains in the region of the rejection opening, whereby fraudulent attempts to cause bad or rejected coins to stack up within the chute a distance sufficient to cause subsequent bad coins to be forced or directed into the good coin discharge opening, may be defeated.

Still another object is the provision of a coin chute having a descending coin passage with a rejection opening at its lower end and through which spurious or objectionable coin elements are rejected, and a good coin opening adjacent the rejection opening and through which accepted coin elements are directed, and selector means in the form of a pawl mounted at the lower end of the chute and having an end portion projecting into the path of coins moving toward or through the rejection opening, and an opposite end arranged to be positioned across the path of coins moving toward the good coin opening, the pawl being constructed to block the movement of coins toward the accepted or good coin opening so long as a spurious or rejected coin remains at or in the region of the rejection opening.

Other novel aspects and objects of the invention will appear as the following description proceeds in view of the drawing, in which:

Fig. 1 is a fragmentary vertical section through

a coin chute embodying the present invention;

Fig. 2 is a fragmentary vertical section of the lower part of the chute, as viewed along lines 2—2 of Fig. 1;

Fig. 3 is a fragmentary vertical elevation, 5 viewed in the direction of lines 3—3 of Fig. 1; while

Fig. 4 is a bottom plan view looking up toward the lower edge of the chute in the direction of lines 4—4 of Fig. 2.

In its broader aspects, the invention is applicable to any type of coin chute having a plurality of discharge openings toward which coin elements move along a common path or chute passage, but for purposes of illustration I have 15 shown the invention incorporated with a type of coin chute shown in my United States application, Serial No. 85,877, filed June 18, 1936.

In general, this preferred form of coin chute includes a substantially flat rectangular chute 20 body 10 consisting of a pair of plate members 11 and 12 (Figs. 1 and 4) which are clamped together and one of which is provided with molded formations 13 providing a devious or tortuous coin passage 14 which descends back and forth from 25 a coin receiving opening (not shown) at the upper end of the chute body into an enlarged discharge area 15 at the bottom of the chute.

Communicating with the enlarged area 15 in the bottom of the chute are a pair of spaced 30 discharge openings 16 and 17, the former being the one through which accepted or good coin elements are discharged, and the other being the rejection opening through which spurious and other coin elements not accepted by the 35 selecting mechanism of the chute are discharged.

The selecting mechanism includes in this instance a pair of permanent magnets 18 and 19 positioned across the chute passage so as to provide a permanent magnetic field through which 40 coin elements must pass and the purpose of which is to retard certain coin elements more than others, the good coin elements always being affected in the same manner so that the travel of such elements in the chute always follows a 45 predetermined behavior. In the enlarged lower chute area 15, there is a ledge portion 20 comprising the lowermost end of the main chute passage and from the end of which a coin element A will be discharged at a rate depending upon 50 its various physical characteristics and the reaction of such element to the several selector means forming part of the chute mechanism. This coin element A may have sufficient velocity to carry it into engagement with the pointed end 55

portion 21 of an adjustable selector 22 mounted in the chute in the portion 16, in which case the coin element would be rebounded (toward the left in Fig. 2) toward the rejection opening 17 or possibly into engagement with the pointed end portion 23 of another adjustable selector 24 and likewise be rebounded into the rejection opening.

On the other hand, the coin element A might follow the predetermined behavior pattern for a good coin so that its velocity would carry it off of the ledge 20 with just sufficient energy to miss both of the selector elements 21 or 23 or to strike the element 23 at a point far enough to the left so that in either case this element would go into the good or accepted coin opening 16.

In the illustration of Fig. 1, the chute unit or body 10 is mounted in somewhat spaced parallel relation to a panel portion 25 constituting one of the walls of a vending or similar machine, the chute being mounted as close to this wall as the extending portions, such as the magnet 19, will permit. Immediately below the discharge or rejection opening 17, there is a return cup 26 having an opening 27 in the cabinet wall 25 which is accessible to the depositor or operator for the purpose of retrieving rejected coins.

It is possible, as illustrated by the dotted line representation in Fig. 1, for one to defraud the selector mechanism by inserting his finger in the return cup and holding it against the mouth of the rejection opening 17 for the purpose of causing rejected coin elements to pile up behind this opening (in the manner illustrated by the coins C, D and E in Fig. 2) in such manner that enough of these coins will collect so that the uppermost one, in this instance, the coin C, will project far enough into the path of a coin such as the coin element A and direct such element into the adjoining coin-discharge opening 16 regardless of whether the coin element A is good or not. Thus, by depositing three slugs in the chute with one's finger blocking the discharge opening 17, the fourth slug would be deflected into the adjoining coin-discharge opening to actuate or release the vending or other machine.

In order to prevent such fraudulent operation of the chute, there is provided the fraud preventive means illustrative in the several figures, particularly Fig. 3, and which comprises a pivoted member or pawl 28 pivotally mounted as at 29 on a bracket 30 attached to the side of the chute near the discharge openings.

One end 31 of the selector or pawl 28 is twisted and offset for projection through an opening 32 in the side wall plate 11 of the chute body just above the spurious coin or rejection opening 17. This offset end portion 31 of the pawl has a rounded edge portion 33 sloping downwardly in the direction of travel of a rejected coin toward the opening 17, so that such a coin will engage this cammed or sloped edge portion 33 and pivot the member 28 (anti-clockwise in Fig. 1) to project the opposite offset and laterally extending end portion 34 of the pivoted member through an opening 35 in the side wall of the chute and across that portion of the coin passage leading to the adjoining coin-discharge opening and between the two selector elements 22 and 24 so as to block the movement of good coins (as well as bad) toward the opening 16.

It will be observed, especially from Fig. 1, that the rounded nose portion 33 of the pawl or selector 28 is spaced upwardly from the lower edge portion of the chute body so that a coin element which has been arrested in this region, as by

stopping the discharge opening with the finger as illustrated in Fig. 1, will cam or pivot the selector arm 28 and hold the blocking arm portion 34 thereof in blocking position so long as the coin element remains in the region of, or substantially opposite, the mouth of the discharge opening 17.

If coins or coin elements are piled up behind the discharge opening 17 in the manner aforesaid, it will be observed that the particular position of the blocking portion 34 of the selector arm is such that when the lowermost blocking coin is released, none of the slugs or coin elements which have been piled up will move into or toward the adjoining coin-discharge opening.

In order to position the feeler or nose portion 31-33 of the selector in blocking position across the passage, there is provided a relatively light leaf spring 36 mounted as at 37 (Fig. 3) on the side of the chute with the free end portion of the spring passed beneath the main longitudinal arm portion 28 adjacent the blocking finger portion 34 thereof so as to pivot the arm in a clockwise direction (Fig. 1) to project the feeler or cam nose 33 across the discharge opening.

It will be apparent that various rearrangements may be made in the particularly described illustration recited herein, and also that the invention is applicable to a variety of types of coin handling mechanism other than that specifically described, and it is therefore my intention that the appended claims shall include all such rearrangements and any modifications or changes in form or location in the device herein described and defined in the appended claims.

Having thus described my invention, what I claim as new and desire to protect by Letters Patent is:

1. In a coin chute of the type having a chute passage discharging into a plurality of adjacent discharge openings, and means for selectively effecting movement of coin elements toward said openings fraud-preventive means in the form of a movable element having a portion disposed substantially across the path of a coin element moving toward one of said discharge openings for engagement and movement by the latter to position another portion of said member in blocking position across the path of a coin element moving toward another and adjacent one of said discharge openings.

2. In a coin chute of the type having a chute passage terminating in a plurality of adjacent coin-discharge openings, and means for selectively effecting movement of coin elements toward said openings fraud-preventive means in the form of a pivoted member mounted adjacent said openings and having a portion disposed substantially in the path of a coin moving toward one of said openings, whereby said member will be pivoted to project another portion thereof in blocking position across the path of coin elements moving toward another of said discharge openings.

3. A coin handling device including a body member providing a descending chute passage having adjacent coin-discharge openings at a lower end thereof, and selector means for selectively directing coin elements into one or the other of said discharge openings, and fraud-preventive means including an arm pivoted adjacent said discharge openings and yieldably urged to project a portion thereof across the path of movement of a coin element toward one of said discharge openings for engagement by said coin

- element to pivot said arm and project another portion thereof across the path of coin elements moving toward another one of said discharge openings.
5. A coin handling device including a chute body providing a descending coin passage having adjacent coin-discharge openings at its lower end, and selector means for directing coin elements variously toward and into said openings, together with fraud-preventive means including a lever arm mounted on said body adjacent said discharge openings and having an offset end portion projected into said chute passage at a point substantially above one of said discharge openings 10 so as to be disposed across the path of a coin moving toward the latter opening to be engaged by said coin to pivot said arm and project an opposite offset end portion thereof into said chute passage to block movement of coin elements toward another one of said discharge openings, together with means yieldably urging said arm to project said first-mentioned offset end portion thereof into position for engagement by coin elements for the purpose and in the manner aforesaid.
15. A coin handling device including a member providing a descending coin passage having a rejection opening at its lower end and an adjoining coin-discharge opening also at its lower end adjacent said rejection opening, selector means in said passage for directing good coins toward said adjoining coin-discharge opening and operable to direct spurious coins toward said rejection opening, together with fraud-preventive means 20 in the form of a pawl pivoted on said body near said discharge openings and having an end portion projected through an opening in said body across the mouth of said rejection opening so as to be engaged and moved by rejected coin 25 elements moving into said rejection opening, said pawl having an opposite end portion movable into said chute passage to block coin elements from movement into said adjoining coin-discharge opening when said first-mentioned end portion of the pawl is engaged and moved by a
- coin element moving into the rejection opening in the manner aforesaid, and spring means normally pivoting said pawl in a direction to project said first-mentioned end portion thereof into the path of coin elements moving toward said rejection opening.
5. A coin chute including a body providing a descending coin passage having a plurality of coin-discharge openings near its lower end and into which coin elements of predetermined physical characteristics are adapted to pass, and fraud-preventive means in the form of an arm pivoted between its ends on said chute near said lower end of the passage and having an offset 10 feeler portion projected through the side of the chute into said passage above one of said discharge openings across the path of coin elements moving into the latter, the opposite end of said arm being offset and movable through an opening in said chute into said passage to block the 15 movement of coin elements toward another one of said discharge openings, together with spring means normally urging said arm to project the first-mentioned feeler portion thereof into coin 20 engaging position across said passage in the 25 manner and for the purpose set forth.
7. In a coin chute having a chute passage and a plurality of discharge openings, selector means in the form of an arm pivoted between its ends and mounted for pivotal movement in opposite 30 directions to project opposite end portions thereof substantially across said passage in the path of coin elements moving toward different ones of said discharge openings, such that a coin element moving toward one of said discharge openings will engage one end portion of said arm to pivot the latter to project the opposite end portion thereof into blocking position relative to another one of said passages, said arm having means yieldably pivoting the same to dispose a particular one of said end portions in blocking position relative to a particular one of said discharge 35 openings.
